Patented Feb. 1, 1927.

UNITED STATES PATENT OFFICE.

MARCUS B. BEHERMAN, OF BROOKLYN, NEW YORK, ASSIGNOR TO THE LOX SEAL CORPORATION, OF BROOKLYN, NEW YORK, A CORPORATION OF NEW YORK.

PILE-WIRE CUTTER.

Application filed October 3, 1924, Serial No. 741,401. Renewed October 25, 1926.

My invention relates generally to a pile cutting means for the type of looms which weave pile fabrics and more particularly to an association with the pile wires generally employed in such looms, of a cutter for cutting the loops as the pile wires are withdrawn.

In looms which I employ pile wires, the warp threads are generally looped over these wires and when it is desired to produce a cut pile fabric, cutters are so associated with the pile wires that upon withdrawal of the wires from the fabric, the cutters will cut through the loops. Due to the rapidity with which these pile wires are thrown in and withdrawn and the number of threads to be cut upon each withdrawal, each cutting edge is subject to a great number of cutting operations in a short time and therefore dulls quickly and such edges must obviously therefore be either frequently resharpened or frequently replaced.

The use of a cutter which is separable from the pile wire for permitting replacement of the blade is attended with a number of problems, among which is that any arrangement for securing the blade in position which on the one hand will serve to hold the blade in association with the pile wire so that it will not shift therein nor will it be accidentally separated therefrom, may on the other hand so secure the blade as to render its removal difficult and time consuming.

One of the important objects of my invention, therefore, is the provision of an arrangement whereby a cutting blade is so associated with the pile wire that while it is fixedly held in position thereon and against accidental movement, its quick and effective removal is permitted.

Looms of the type referred to are already provided with pile wires and it is one of the important objects of my invention to so devise the cutter and its manner of association with a pile wire that the cutter can be associated with the conventional form of pile wire without requiring a replacement of the pile wires or any substantial change or reconstruction therein.

My invention further involves the provision whereby a blade of a flexible wafer type made from sheet material may be employed and an arrangement for so supporting the blade that will not require any sub-

stantial flexing of the blade either for purposes of insertion or for removal.

My invention further involves the provision of a simple, inexpensive and efficient cutting blade and of a novel, simple, readily operable, inexpensive manner of associating the blade with the pile wire so as to permit the blade on the one hand to perform its function at a maximum of effectiveness, and at the same time to permit of its quick removal and replacement.

For the attainment of these objects and such other objects as may hereinafter appear or be pointed out, I have illustrated one embodiment of the invention in the drawings wherein—

Fig. 1 is an elevational view of the pile wire with the blade in position.

Fig. 2 is an enlarged view similar to that of Fig. 1 showing the blade holder portion of the pile wire.

Fig. 3 is a side elevational view of the cutter.

Fig. 4 is a section taken on line 4—4 of Fig. 2; and

Fig. 5 is a horizontal section taken on line 5—5 of Fig. 2.

In Fig. 1, I show the pile wire, the front end of which 10 forms the blade holder and which front end may be either integral with the pile wire or in the form of an attachment thereto. This holder is preferably made from a sheet metal blank and bent upon itself longitudinally so as to provide the walls 11 and 12 and the bottom 13 which define channel 14, in which the knife is adapted to be moved and secured in its predetermined position.

Upon viewing the figures of the drawing, it will be observed that the wall 11 is provided at the front end thereof, with the spoon-like member 16 which extends beyond the wall 12 and is wider than the wall 11 and which preferably narrows towards its front end 17 and which is curved all for purposes that will be clearly understood for those skilled in the art.

The wall 12 has at its front end, the upwardly extending finger 20, the uppermost portion of which is bent at an angle thereto and across the channel 14 and into registry with an opening 22 in the member 16, within which opening it is secured in any preferred or desired manner, as by brasing or welding. This portion 20 of the wall 12

has extending therefrom in the forward direction the finger 24 which has a portion depressed inwardly as at 25 so as to produce a teat extending part way across the channel 14 and upon viewing Fig. 5, it will be observed that the portion 16 of the wall 11 is provided with a similar teat 26 similarly extending part way into the channel 14, the two teats being in registry so as to form a restriction of the channel at this point. These teats are preferably each arranged so as to provide an inclined surface 25' and 26' with which the knife coacts in its movement to locking position and are arranged to provide an inclined surface 25'' and 26'' in the opposite direction so as to permit of a release of the blade.

The knife 30 which I prefer to employ with this embodiment of my invention is preferably of the sheet metal wafer type and is of a dimension to be received in the channel 14 for movement thereon with its lower edge 31 seated on the bottom 13 of the channel 14. The cutting edge 32 of this knife is inclined as shown, the height of the wall 11 and 12 and of the channel, being such that the major portion of the cutting edge 32 is exposed for cutting operation.

The blade 30 is further provided with the rearward extending portion 33 provided with the slot 34 extending downwardly and preferably although not necessarily open to the lower end of the blade.

In the assembly of the blade with the holder, the blade is introduced into the channel 12 inwardly or to the right of the finger 20 and then moved along toward the forward or the front end of the pile wire with the lower end of the blade 31 seated on the bottom 13 and the portion 33 of the blade moved beneath the cross piece 21 as shown in Fig. 4. The height of the part 33, is about equal to the distance of this cross piece 21 from the bottom 13. As this blade is moved along as described, its rear-most portion 36 is brought in contact with the two opposed teats 24 and 25 and upon a continued movement, these teats will be forced apart laterally of each other at least sufficiently to permit this portion of the blade to pass therebetween until the slot 34 is brought into registry with the opposed teats, upon which these teats move toward each other and into the slot 34. In this position, the blade is held against movement in either direction except upon the application of an abnormal pressure and is held positively against movement toward the pointed or outer end of the pile wire by the engagement of the shoulder 38 on the blade with the shoulder 35 on the portion 20.

The blade can be removed either by applying a sufficient pressure thereto to the right in Fig. 1 so as to cause it to force the two teats 25 and 26 apart or by forcing the

teats apart in any other manner or where for any reason whatsoever, it is so desired, the portion 36 can be broken off upon which the blade can be removed easily which action is permitted by the fact that the channel 14 is open laterally at this point, because of the difference in the length of the walls 11 and 12.

The engagement of the cross piece associated at the top of the blade will prevent any tendency of the blade to rotate about the teats 25 and 26.

By placing teat 25 adjacent the extreme end of the finger 24, I provide a construction whereby this finger 24 is made relatively more flexible than the rest of the holder and in this manner, one insertion and removal of the blade is made less difficult.

Having thus described my invention and illustrated its use what I claim as new and desire to secure by Letters Patent is—

1. For use in looms for weaving pile fabrics, a holder adapted to form part of a pile wire and having a channel to receive a cutting implement with one edge of the implement seated on the bottom of the channel, abutments extending inwardly on the opposite walls of said channel, said abutments being forced inwardly from the walls of the channel and being integral therewith at all points, a cutting implement arranged so as to be received in said channel and provided with a slot opened to one edge thereof and arranged to register with the abutments when the blade is moved along the channel whereby as said implement is moved along the channel, the abutments on the walls of the channel will be forced apart until the slot in the implement is in registry with, when the abutments will move toward each other and position themselves within the slot of the implement to hold the implement against movement in either direction.

2. For use in looms for weaving pile fabrics, a holder adapted to form part of a pile wire and having a channel to receive a cutting implement or blade with one edge of the implement seated on the bottom of the channel, one of the walls of the channel being extended longitudinally beyond the other whereby the channel is open laterally opposite such extended portion and means on said holder for holding the blade against movement in said channel said means including members extending inwardly on the opposite walls of the channel and oppositely to each other, the member on the short wall being positioned adjacent the extreme end thereof, whereby an implement provided with a cut away portion can be moved into the channel to bring said cut away portion thereof into registry with the opposed members for holding the implement in position.

3. For use in looms for weaving pile fabrics, a holder adapted to form part of a

pile wire and having a channel to receive a cutting implement with one edge of the implement seated on the bottom of the channel, one of the walls of the channel being extended longitudinally beyond the other whereby the channel is opened laterally opposite said extended portion, a finger projecting forwardly from the shorter wall and spaced from the bottom of the channel and a teat projecting inwardly from and adjacent the outer edge of said finger, whereby a knife having a cut away portion therein and moved along said channel will engage said teat and force it laterally until the cut out portion of the implement is in registry with the teat upon which the teat will move into the cut out portion to hold the blade in position.

4. For use in looms for weaving pile fabrics, a holder adapted to form part of a pile wire and having a channel to receive a cutting implement with one edge of the implement seated on the bottom of the channel, one of the walls of the channel being extended longitudinally beyond the other whereby the channel is opened laterally opposite said extended portion, a finger projecting forwardly from the shorter wall and spaced from the bottom of the channel and a teat projecting inwardly from and adjacent the outer edge of said finger, whereby a knife having a cut away portion therein and moved along said channel will engage said teat and force it laterally until the cut out portion of the implement is in registry with the teat upon which the teat will move into the cut out portion to hold the blade in position, and a teat on the longer wall extending inwardly and opposed to the first mentioned teat.

5. For use in looms for weaving pile fabrics, a holder adapted to form part of a pile wire and having a channel to receive a cutting implement with one edge of the implement seated on the bottom of the channel, one of the walls of the channel being extended longitudinally beyond the other whereby the channel is opened laterally opposite said extended portion, a finger projecting forwardly from the shorter wall and spaced from the bottom of the channel and a teat projecting inwardly from and adjacent the outer edge of said finger, whereby

a knife having a cut away portion therein and moved along said channel will engage 55 said teat and force it laterally until the cut out portion of the implement is in registry with the teat upon which the teat will move into the cut out portion to hold the blade 60 in position, means spaced from said teat to engage the implement and prevent its rotation about the teats.

6. For use in looms for weaving pile fabrics, a holder adapted to form part of a pile wire and having a channel to receive 65 a cutting implement, one of the walls of the channel being extended longitudinally beyond the other whereby the channel is opened laterally opposite said extended portion, a projection formed inwardly of the 70 outer edge of the shorter wall, and extending inwardly into the channel, whereby a knife moved along said channel will engage said projection and force it laterally to bring a portion of the implement in registry 75 with the projection to cause the two to interlock.

7. For use in looms for weaving pile fabrics, a holder adapted to form part of a pile wire and having a channel to receive 80 a cutting implement, one of the walls of the channel being extended longitudinally beyond the other whereby the channel is opened laterally opposite said extended portion, a member projecting inwardly into the 85 channel from the shorter wall, and so arranged that upon the movement of the implement in the channel, the projection will permit the blade to automatically pass thereby to cause the projection to interengage 90 with a portion of the implement, so as to hold the blade against movement in either direction.

8. A pile wire blade holder having a recess adapted to receive a blade, and presenting a projection which is adapted to interengage with and lock the blade in the recess, said blade holder having a flexible portion other than said projection, adapted to be flexed to move said projection laterally 100 thereby to withdraw it from its locking engagement with said blade.

In testimony whereof, I have signed this specification, this 26th day of September, 1924.

MARCUS B. BEHRMAN.
